UNITED STATES PATENT OFFICE.

ALEXANDER HORVATH, OF CHICAGO, ILLINOIS.

DESIGN FOR A BREAST WATCH.

Application filed August 31, 1921. Serial No. 497,391. Term of patent 3½ years.

To all whom it may concern:

Be it known that I, ALEXANDER HORVATH, a citizen of the United States, residing at Chicago, in the county of Cook, State of Illinois, have invented a new, original, and ornamental Design for a Breast Watch, of which the following is a specification, reference being had to the accompanying drawing, forming a part thereof.

Fig. 1 is a rear elevational view of a breast watch showing my new design; Fig.

2 is an edge view of the same device; and Fig. 3 is a front elevational view of the central portion of the device.

I claim:

The ornamental design for a breast watch, as shown.

ALEXANDER HORVATH.
